UNITED STATES PATENT OFFICE

FRANK G. CARRINGTON, OF ANNISTON, ALABAMA, ASSIGNOR TO FERRIC ENGINEERING COMPANY, OF ANNISTON, ALABAMA, A CORPORATION OF DELAWARE

PIPE-EXTRACTING APPARATUS

Application filed July 6, 1927. Serial No. 203,832.

This invention relates to the centrifugal casting of pipe, and more particularly refers to an apparatus for extracting a pipe from a rotating mold.

In a centrifugal casting process molten metal is poured in rotating molds and there maintained until it has sufficiently hardened for removal. In order to prevent an efflux of the liquid metal from the ends of the molds, cores are inserted in the molds. The cast pipes are usually extracted from the molds by gripping and pulling the cores, thus preventing abrasion of the recently cast pipe. With certain types of cores, however, the pulling device grips the pipe itself. My invention is adapted for use with any type of core.

Over a casting operation there is a substantial increase in the heat of the mold—to such an extent that artificial cooling is necessary. If rotation of the mold is not continuous, an uneven circumferential cooling of the mold results, which causes warpage of the mold and pipe. An uneven texture of the pipe itself also results from stopping the mold's rotation, for the texture of the pipe is dependent on its rapidity of cooling; and when a pipe cools it shrinks and contacts with the mold along only the bottom, where the cooling is more rapid than at other points on the circumference.

The necessity for continuous rotation is therefore apparent. While it is true that some of the devices heretofore used for pulling a pipe from a mold have been capable of operation while the mold rotates, they have failed in efficiency and satisfaction.

The principal disadvantage has been their inability to operate when the mold becomes warped. Even when rotation of the mold is continuous, there nevertheless develops a slight warpage which causes a gyration of the end of a mold when rotating. And this gyration increases along the center line projected from the end of the mold. The more a pipe is withdrawn from a mold therefore, the greater will be its gyration.

The pipe pullers heretofore used have failed to provide for this misalignment of the axes of the mold and the puller.

To overcome the difficulties inhering in the former devices is one of the objects of this invention.

Another object is to provide a pipe extracting device compact and economical of construction and operation.

Yet another object is to provide a pipe extracting device capable of operation when misaligned with a mold.

And a still further object is to provide a device for extracting a pipe from a warped mold.

To accomplish the above objects, and other important advantages as will appear more fully herein, my invention comprises in general gripping means and flexibly connected therewith tractive means.

In order to more fully comprehend the scope of my invention, but in no way limiting myself to the details of construction therein set forth, reference is made to the accompanying drawings in which similar numerals indicate the same parts of the device.

Figure 1 is a side elevational view of the device just before gripping a head core;

Fig. 2 is a side elevational view of the device in operative position within the mold;

Fig. 3 is a side elevational view of the device in inoperative position;

Fig. 4 is a bottom plan view of the device;

Fig. 5 is a longitudinal sectional view along the line 5—5 of Fig. 2 looking in the direction of the arrows;

Fig. 6 is a front plan view of the apparatus;

Fig. 7 is a cross sectional view of the device along the line 7—7 of Fig. 2, looking in the direction of the arrows.

Referring more particularly to Fig. 1, a gripping device 1 is shown. This device comprises a head member 2 provided with a centrally positioned frusto-conical aperture 3, as is more clearly set forth in Fig. 5. The base of the cone is in the rear of the head member, as at 4, and converges toward the front of the member. The front portion of the aperture is provided with a concave seat 5 which is adapted to receive a partially spherical set nut 6. The set nut 6 is threaded

80

85

90

95

100

on a shaft 8. When a pull is exerted on the shaft, the set nut and seat 5 act, in effect, as a ball and socket joint, and the shape of the aperture 3 permits the shaft to swing in an arc in any plane. Lock nuts 9 and 11 maintain the set nut 6 in position on the shaft. It will be observed that the head member 2 is adapted to slide to the right on the shaft 8, but its movement to the left is limited by the set nut 6.

As shown in Fig. 6, the head member 2 is bifurcated as at 12 and 13. Between the arms 14 and 15, provided by the bifurcation at 12, there is pivotally mounted a dog 16. Another dog 17 is pivotally mounted between arms 18 and 19 of the bifurcation 13.

In Figures 1 to 3, there is shown in more detail the shape of the dogs. These dogs are adapted to contact with a wall 21 of a frusto conical aperture 22 in a head core 23. While I have shown the dogs gripping a head core, they may be clamped on the pipe itself or an end ring core may be used. It is to be noted that the wall of the aperture converges toward the outside, or face 24, of the core. This shape of the aperture minimizes the possibility of the apparatus slipping from the core when the dogs are in operative position and a pull is exerted.

Referring to Fig. 6, there are pivotally attached to either side of the dog 16 by a bolt 25, or other suitable means, arms 26 and 27. Similar arms 28 and 29 are attached to the dog 17 by a bolt 31 or other appropriate pivoting means. It will be observed that reciprocation of the arms results in oscillation of the dogs 16 and 17.

A plate 32 is secured to the head member 2 by a bolt 33, which serves as a pivot for the dog 16, and a bolt 34 on which the dog 17 pivots. On the opposite side of the head member 2 a plate 35, similar in all respects to plate 32, is mounted, and held by the other ends of the bolts 33 and 34. It is of course understood that other appropriate means may be employed for securing the plates 32 and 35 to the head member 2.

The plates 32 and 35 extend to the rear of the head member 2, and at the opposite end terminate in a flange 36. As shown more particularly in Fig. 7, the flange 36 is of a disk formation provided with a central aperture 37. The shaft 8 projects through the aperture, and it will be noted that the size of the aperture is sufficient to permit radial movement of the shaft therein, resulting from the swing of the shaft in the seat 5.

In the plate 32 there is a rectangular cut away portion 38, and in the plate 35 a similar aperture is provided. Within the apertures slide cross heads 39 and 41, referring to Fig. 7. The member 39 is provided with flanges 42 and 43 which project beyond the aperture and rest upon the outside of the plate 32. Cross head guides 44 and 45 are mount-

ed on the plate 32 by bolts or nuts 46, or other suitable means. The cross head guides are provided with flanges 47 which overlap the flanges 42 and 43 on the cross head and prevent all except a sliding movement of the cross head. The cross head 41 has flanges 48 and 49, similar to those on the cross head 39. Guides 51, and 52, provided with flanges 53, similar to 47, are mounted on the plate 35 by means of bolts 54.

At the front of each cross head there is a right angular projection, 55 for the cross head 39, and 56 for the cross head 41. These projections are attached on their interiors to the arms 26, 27, 28 and 29 by means of bolts 57. Attached to the bolts are spring members 58, which are also held by means of screws 59 to the flange 36. With this arrangement there is a tendency for the cross heads to remain at the rear of the apertures 38, and, on removal from that position, to return thereto. It will also be observed that a movement of the cross heads in their guides results in an oscillation of the dogs about their respective pivots. When the cross head is moved to the front of the guides, the dogs are thrown into operative position, and when the spring returns the cross head to the rear of the guides, the dogs are substantially flat upon the device.

Referring to Figs. 5 and 7, there is shown mounted on the inside of the cross head 39, and separated therefrom by a washer 61, a lever 62. A bolt 63 securely fastens the lever to the cross head. A lever 64 is mounted on the cross head 41 by means of a bolt 65 and washer 66. The ends of the levers 62 and 64 opposite their ends of attachment to the cross heads are partially rounded, as at 67, in order to reduce the friction between the lever and the core face 24.

By means of a bolt 68 the lever 62 is attached to a link 69. A similar link 71 is attached to the lever 64 by means of a bolt. The link 69 is joined by means of a bolt 72 to one arm 73 of a three-armed bell crank.

The plate 32 is provided with a downwardly projecting portion 74 in which an arcuate slot 75 is cut. A similar projection 76 is provided on the plate 35, as well as an arcuate slot. These slots conform to the arcs described by bolt 72 as it swings about the bell crank.

Referring to Figure 7 it will be observed that the bolt 72 projects through the slot and the extent of the arc described by it is limited by the length of the slot. In the same figure there is shown a bolt 77 which joins the link 71 to an arm 78 similar to arm 73. This bolt also projects through the slot in the projection 76. The arms 73 and 78, it will be noted, are on the inside of the plates 32 and 35, and are mounted on a crank 79.

An arm 81 angularly disposed to the arms 73 and 78 and mounted on the middle of the

5 crank, extends below the bottom of the projections 74 and 75. Another arm 82, also mounted on the middle of the crank 79, projects upwardly, and is attached to a spring 83 which is secured to a plate 84 which connects the plates 32 and 35. The plate 84 also serves as a support member for the plates 32 and 35.

10 There is shown in Figures 2 and 3 an arm 85 which is in the plane of the arm 81, the purpose thereof being more fully described hereinafter.

15 Referring to Figures 4 and 5, it is to be observed that the plates 32 and 35 are bent, as at 86, and that the arms 26, 27, 28 and 29 are bent, as at 87. These members are bent in order to permit the shaft 8 to swing about the seat 5, and by this arrangement there is no obstruction to such swing except the size of 20 the aperture 37 in the flange 36. The shaft therefore may pull the pipe from the mold even though there is a gyration of the end of the mold.

25 There is attached to the end of the shaft, as shown in Fig. 5, a rotatable joint. This joint comprises a casing 88 in which there is a cavity 89. Fixed in one end of the cavity is a disk 91 provided with a ball race for ball bearings 92. Opposite the disk 91 is another disk 93, which revolves and is also provided with a ball race. A flanged disk 94 is mounted on the shaft 8. The casing 88 is threaded on its interior and is adapted to receive a member 95 in which a flexible tractive means 96, such as a cable, rope or chain is secured. There is shown a cable which is inserted and spread, after which lead is poured to prevent the cable from being pulled from the member 95. With this joint the shaft 8 may revolve while the cable, or other flexible means, remains stationary.

30 A suitable grip (not shown) is provided so that an operator may insert the device while the core is rotating. A sleeve might rotatably surround the shaft 8, which would remain stationary while the shaft and apparatus is revolving.

35 Fig. 1 depicts the apparatus just prior to insertion in the core. I shall describe the operation of only cross head 39 and its related members, it being understood that cross head 41 operates in exactly the same way. The arm 73 is lowered until the bolt 72 rests in the bottom of the slot 75. The bell crank will be held in this position by reason of the pull exerted by the spring 83. The springs 58 maintain the cross head in the rear of the aperture 38.

40 As the apparatus is further inserted in the core, as shown in Fig. 2, the end 67 of the levers 62 contacts with the core facing 24. Further forward movement of the device causes the lever 62 to pivot at its point of attachment to the link 69. Inasmuch as the bolt 72 is below the direction of the force ap-

plied, the link 69 serves as a rigid pivot. This means that the upper portion of the lever 62 is moved forward, and in so doing the cross head 39 is forced to the front of the aperture 38. This in turn forces the arms 26 and 28 forward and the dogs 16 and 17 are spread and contact with the aperture walls 21.

45 When the dogs have firmly gripped the core or pipe, the apparatus is ready to pull the pipe from the mold. It will be observed that the device grips the core or pipe more firmly when a pull is exerted. If the mold is of the axially stationary type, the cable is wound up on a drum, or other means are employed to exert a pull upon it. If the mold moves longitudinally, the end of the cable may be securely fastened and the mold withdrawn from it. With a long cable and rod the effects of the mold's gyration is reduced, and it is therefore desirable to have a cable 50 and rod of considerable length.

55 The mold continues to rotate while the pipe and core are being extracted therefrom and when the pipe is entirely withdrawn from the mold, it is supported by suitable means. As the core is withdrawn, the arm 81 strikes the member 85. This revolves the crank, which in turn raises the arm 73. When the arm 73 passes above the horizontal, the pivot arrangement collapses and the springs 58 return the cross head 39 to the rear of the aperture. The dogs and bell crank arrangement are then in the position shown in Fig. 3 and the apparatus may be withdrawn from the core.

60 It will be seen from the foregoing that there need be no cessation in the mold's rotation in order to remove the casting by my invention. The pulling device may be inserted, clamped to the pipe or core, and the pipe extracted from the mold, all while the mold is rotating at its ordinary, or a reduced, speed.

65 It will also be seen that my invention operates efficiently even with a warped mold. Regardless of the gyration of the mold, the rod 8 and the cable remain taut and continue to exert the same pull on the head member 2. As above pointed out, the shaft swings about the seat 5 and does not contact with any of the members of the apparatus except the flange 36.

70 Although a particular embodiment of my invention has been set forth in the foregoing specification and in the appended drawings in considerable detail, it is to be understood that many alterations and modifications of structure may be made therein. Any such changes, it is to be understood, however, are to be limited only by the scope of the appended claims.

75 I claim:

80 1. A device for extracting a pipe from a rotating mold comprising a head member 75 adapted to be extended within the pipe, a

body portion mounted on said head member, engaging members pivoted on the head member, resilient means on the body member to maintain the engaging members normally in 5 inoperative position, a lever carried by the body member and connected with the resilient means to throw the engaging members into operative position and means associated with the lever to return said lever to inoperative position.

2. A device for extracting a pipe from a rotating mold comprising a body member, having a slot therein, a crosshead slidable in said slot, pipe-gripping means carried by 15 said body member, links connecting said gripping means with said crosshead, a lever pivoted to said crosshead, a floating fulcrum for said lever floatingly carried by said body member and means carried by the free end of said lever for engaging a mold for actuating the crosshead.

3. A device for extracting pipe from a rotating mold comprising a body member, having a slot therein, a crosshead slidable in 25 said slot, pipe-gripping means carried by said body member, links connecting said gripping means with said crosshead, a bell crank carried by said body member, a link connected with one arm of the bell crank, 30 a lever pivoted to the free end of said link, said lever having one end pivoted to the crosshead and adapted to actuate the same upon engagement between the free end of said lever and the mold.

4. A device for extracting pipe from a rotating mold comprising a body member having a slot therein, a crosshead slidable in 35 said slot, pipe-gripping means carried by said body member, links connecting said gripping means with said crosshead, a bell crank carried by said body member, a link connected with one arm of the bell crank, 40 a lever pivoted to the free end of said link, said lever having one end pivoted to the crosshead and adapted to actuate the same upon engagement between the free end of 45 said lever and the mold, and means for shifting the bell crank to release the gripping means.

5. A pipe puller comprising a body portion, gripping means carried thereby, a crosshead slidable in said body, a lever pivoted to 50 said crosshead, means connecting the gripping means and crosshead, the free end of said lever adapted to cooperate with the mold and toggle means connecting the lever with the body portion.

6. A pipe puller comprising a body portion, gripping means carried thereby, a crosshead slidable in said body, means connecting the gripping means and crosshead, a lever pivoted to the crosshead, the free end of said lever adapted to cooperate with the mold 55 toggle means connecting the lever with the

body portion, and means for actuating the toggle means.

7. A pipe pulling device comprising a body member, pipe engaging elements mounted on said member, flexible means carried by the body member, said means being cooperatively associated with the pipe engaging elements and said body member for resiliently urging said pipe engaging element into inoperative position and means carried by the body member for moving the pipe engaging elements into operative position.

8. A device for removing castings from rotary molds comprising a body member adapted to be inserted in the casting, casting engaging elements carried by the member, resilient means carried by the body member for normally holding the engaging elements in inoperative position, a lever carried by 80 the body member and connected to the engaging elements, operable upon engaging the mold for moving the engaging elements into operative position.

9. A pipe pulling device comprising a body member, pipe engaging elements mounted on said member, flexible means carried by the body member, said means being cooperatively associated with the pipe engaging elements and said body member for 90 resiliently urging said pipe engaging element into inoperative position, means carried by the body member for moving the pipe engaging elements into operative position and tractive means directly and flexibly 95 connected to the body portion.

10. A device for extracting pipe from a rotating mold comprising a body member adapted to be inserted within the pipes, gripping means on said body member, means carried by the body member for actuating the gripping means and resilient means for returning the gripping means to inoperative position when the pipe is removed from the mold, all of said means being cooperatively 100 associated on the body member.

11. A device for extracting pipe from a rotating mold comprising a body member adapted to be inserted within the pipes, gripping means on said body member, means carried by the body member for actuating the gripping means and resilient means for returning the gripping means to inoperative position when the pipe is removed from the mold, all of said means being cooperatively 115 associated on the body member and tractive means connected with the extracting device by a ball and socket joint.

12. A device for extracting pipe comprising a member adapted to be inserted in the 125 pipe, means carried by the member for gripping the pipe, a socket portion of a ball and socket joint mounted on said member, a ball-like member in said socket and tractive means connected to said ball.

13. A pipe extracting device comprising a body member, dogs pivoted on the body member, a crosshead slidably mounted on said body member, links pivoted to the dogs and said sliding member, resilient means for urging the sliding member to a determined position to retain the dogs in inoperative position and means connected with the sliding crosshead for sliding the same to move the dogs to operative position. 10
14. A pipe extracting device comprising a body member, dogs pivoted on the body member, a crosshead slidably mounted on said body member, links pivoted to the dogs and said sliding member, resilient means for urging the sliding member to a determined position to retain the dogs in inoperative position, means connected with the sliding crosshead for sliding the same to move the dogs to operative position and flexible tractive means connected to said device. 20
15. A pipe pulling device comprising a body member, pipe engaging elements mounted on said member flexible means carried by the body member, said means being cooperatively associated with the pipe engaging elements and said body member for resiliently urging said pipe engaging element into inoperative position, means carried by the body member for moving the pipe engaging elements into operative position and flexible tractive means connected to said device. 25
16. A pipe pulling device comprising a body member, pipe engaging elements mounted on said member, flexible means carried by the body member, said means being cooperatively associated with the pipe engaging elements and said body member for resiliently urging said pipe engaging element into inoperative position, means carried by the body member for moving the pipe engaging elements into operative position, and other means carried by the body member for actuating said last mentioned means so that the engaging elements can be moved to an inoperative position. 40
17. A device for removing castings from rotary molds comprising a body member adapted to be inserted in the casting, casting engaging elements carried by the member, resilient means carried by the body member for normally holding the engaging elements in inoperative position, a pivot pin shiftably mounted on said body, a lever carried by said pin for moving the engaging elements into operative position and means associated with said pin for shifting the same to move the engaging elements to inoperative position. 55
18. A device for removing castings from rotary molds comprising a body member adapted to be inserted in the casting, casting engaging elements carried by the member, resilient means carried by the body member for normally holding the engaging elements 60
- in inoperative position, a pivot pin shiftably mounted on said body, a lever carried by said pin for moving the engaging elements into operative position, means associated with said pin for shifting the same to move the engaging elements to inoperative position and means exterior of the mold for actuating the shifting means. 70
19. A pipe pulling device comprising a body member, pipe engaging elements mounted on said member flexible means carried by the body member, said means being cooperatively associated with the pipe engaging elements and said body member for resiliently urging said pipe engaging element into inoperative position, means carried by the body member for moving the pipe engaging elements into operative position, other means carried by the body member for actuating said last mentioned means so that the engaging elements can be moved to an inoperative position, and tractive means flexibly connected to the body member. 75
20. A pipe pulling device comprising a body member, pipe engaging elements mounted on said member flexible means carried by the body member, said means being cooperatively associated with the pipe engaging elements and said body member for resiliently urging said pipe engaging element into inoperative position, means carried by the body member for moving the pipe engaging elements into operative position, other means carried by the body member for actuating said last mentioned means so that the engaging elements can be moved to an inoperative position and tractive means universally connected to said body member for withdrawing the device and casting from the mold. 85
21. A pipe pulling device comprising a body member, pipe engaging elements mounted on said member flexible means carried by the body member, said means being cooperatively associated with the pipe engaging elements and said body member for resiliently urging said pipe engaging element into inoperative position, means carried by the body member for moving the pipe engaging elements into operative position, other means carried by the body member for actuating said last mentioned means so that the engaging elements can be moved to an inoperative position, rigid tractive means universally connected to said body member and flexible means rotatively connected to the rigid tractive means. 105
22. A device for extracting castings from a rotating mold comprising a member insertable in the casting, means on said member for gripping the casting, and tractive means universally connected to the body member for withdrawing the casting from the mold under misaligned conditions without impairing the operation of the gripping means. 125
23. A pipe extracting device comprising a 130

member adapted to be inserted in the pipe, dogs pivoted on said member adapted to grip the pipe, resilient means for actuating the dogs, rigid tractive means universally connected to the member, and flexible tractive means rotatably connected to the rigid tractive means, said tractive means cooperating to permit the pipe to be extracted from a misaligned mold.

10. 24. A device for extracting a pipe from a rotating mold comprising a body, pipe engaging means mounted on the body, means on the body tending to maintain the pipe engaging means in inoperative position, means on said body and associated with the pipe engaging means adapted to contact with a surface for operating the engaging members and other means carried by the body and operatively associated with the operating means to disengage the pipe engaging means.

15. 25. In a device for extracting pipe from a rotating mold, a body, pipe engaging means on said body, tractive means comprising a shaft connected with said body by a universal joint, and a flexible tractive member rotatably connected with said shaft.

20. 26. A device for extracting pipe from a rotating mold comprising a body member having a slot therein, a crosshead slidable in said slot, pipe gripping means carried by said body member, links connecting said gripping means with said crosshead, a lever pivoted to said crosshead, a floating fulcrum for said lever mounted in a slot in said body member, means carried by the free end of said lever for engaging a mole for actuating a crosshead and means on said body member for moving the fulcrum in the slot so that the pipe gripping means will be rendered inoperative.

25. 40. In testimony whereof I affix my signature.
FRANK G. CARRINGTON.
